Application March 30, 1937, Serial No. 133,793
In Poland September 17, 1936

22 Claims. (Cl. 179—171.5)

The present invention relates to electrical circuits, more particularly to alternating current circuits, and among the objects of the invention are the provision of means for and a method of varying and controlling the phase of an alternating current such as a high frequency current in a radio circuit or the like.

A more specific object of the invention is the provision of a system of and a method for converting alternating currents, more particularly radio frequency currents of varying amplitude into currents of varying phase.

A further object is to provide an arrangement for converting alternating currents having different amplitudes into currents of substantially the same amplitude and relative phase difference proportional to the initial amplitude relation.

Another object is the provision of a system for and a method of obtaining a combined amplitude and phase modulation of two mutually modulated alternating currents which may be recombined into pure amplitude modulated currents to increase the efficiency of modulation.

A further object is the provision of a system for and a method of producing single side band modulated carrier signals with or without suppression of the carrier, wherein either of the side bands may be selected as desired in an easy and simple manner.

Still a further object is the provision of a simple and efficient device and a circuit and method of operating therefor for effecting phase modulation of a carrier current with or without subsequent conversion of the phase modulated carrier into pure amplitude modulated carrier.

The above and further objects and advantages of the invention will become more apparent from the following detailed description taken with reference to the accompanying drawing illustrating several practical exemplifications of the invention.

In the drawing wherein like reference characters identify parts of like function throughout the different views thereof,

Figure 1 illustrates a phase modulating system according to the invention for use in a wireless transmitter or the like with final recombination of the phase modulated carrier current into an amplitude modulated carrier.

Figures 2 to 5 are theoretical diagrams explanatory of the function and operation of the system according to Figure 1.

Figure 6 illustrates a single side band transmission system embodying the principle of the invention.

Figure 7 illustrates the invention as embodied in a high frequency microphone device for effecting a phase modulation.

Figure 8 illustrates a complete modulating device or

microphone according to the invention with final conversion of the phase modulated carrier current into an amplitude modulated carrier.

Figure 9 is a diagram explanatory of the function of the circuit of Figure 8.

With the above objects in view, the invention generally involves a method for combining or reacting upon one another alternating currents through a circuit arrangement comprising substantially a pair of coupled resonant circuits simultaneously excited by potentials of like frequency which may be supplied from a common source of oscillation or carrier current generator. The circuits are separately tuned to resonance with the exciting current and then coupled together inductively or in any other suitable manner.

In an arrangement of this type, if provision is made that approximately $R_1=R_2=wM$ or in other words that the non-reactive or ohmic impedances of both circuits are substantially equal to one another and to the mutual coupling impedance between the circuits, then the currents, if both circuits are excited by potentials of the same frequency, are defined by the following theoretical expressions well understood by those versed in the art:

$$I_1 \sin (wt + \varphi_1) = \frac{E_1 R_2}{Z} \sin wt - \frac{E_1 w M}{Z} \cos (wt + \varphi_0) \quad \text{I} \quad 30$$

$$I_2 \sin (wt + \varphi_2) = \frac{E_2 R_1}{Z} \sin (wt + \varphi_0) - \frac{E_2 w M}{Z} \cos wt \quad \text{II} \quad 35$$

wherein

I_1 and I_2 represent the amplitudes of the currents in the respective circuits,

φ_1 and φ_2 the phases of the respective currents, E_1 and E_2 the electromotive forces impressed upon the circuits,

R_1 and R_2 the loss of non-reactive impedances of the circuits,

L_1 and L_2 the values of the self inductances of the circuits,

C_1 and C_2 the values of the capacities of the circuits,

M the coefficient of the mutual induction or coupling between the circuits,

φ_0 the phase difference between the currents in the circuits.

$$w = 2\pi f$$

with f representing the frequency of the currents and

$$Z = \left(wL_1 - \frac{1}{wC_1} \right) \left(wL_2 - \frac{1}{wC_2} \right) - R_1 R_2 - w^2 M^2$$

From the above equations it follows that the phases of the currents and also their amplitudes

are dependent both on the magnitude of the electromotive forces E_1 and E_2 impressed upon the circuits and on the phase difference between them.

5 Such a phase spreading or control arrangement and method has great utility for numerous purposes and applications, some of which have been illustrated in the exemplifications shown.

Referring to Figure 1 there is shown a phase 10 modulating system suited for broadcast transmitters and the like and utilizing both amplitude and phase modulation for improving the operating conditions and efficiency of the system. Phase modulating arrangements of this 15 type known in the art usually comprise means for generating a carrier current of constant amplitude, the phase of which is changed in accordance with the modulating signal variations. Alternatively, both phase and amplitude may be 20 varied simultaneously. The latter system has great use for wireless transmitters in order to improve the overall energy conversion efficiency of the system. In known arrangements of this type, usually two amplifying channels are provided 25 fed with separate carrier components the phase difference between which is varied in accordance with the variations of modulating signals. The phase modulated currents are then recombined in a common output or utilization circuit to produce a resultant amplitude modulated current.

In the drawing, details of parts not necessary for an understanding of the invention have been indicated schematically only to simplify the description and drawing.

The system according to Figure 1 comprises a driver shown at 10 which may be any known type of high frequency oscillator or generator such as a vacuum tube oscillator. The carrier current supplied by the driver is divided into two components each of which is transmitted through a separate amplifying branch or channel. The outputs of the amplifying channels in the example shown are recombined in a common utilization circuit. In the example illustrated, the first channel comprises a pre-amplifier 11 having a final amplifying stage 15. The amplified carrier currents supplied by the latter are impressed through a coupling condenser 17 upon a resonant 40 circuit comprised of a capacity 19 and inductances 20, 21 in parallel. This resonant circuit is coupled with the grid of a final amplifier stage or tube 27 by means of a pair of coupling condensers 25 and 30 and a grid leak resistance 32 45 in a manner well known in the art.

Similarly, the second channel comprises a pre-amplifier 12 which in the example shown serves also as a modulator and has a final amplifying stage represented by the amplifying tube 16. The 50 modulating currents may be supplied from any suitable source such as a microphone to be connected at 14 and are impressed upon the amplifier or modulator 12 of the carrier suppression type through a low frequency transformer 13. The modulation may be affected in accordance 55 with any one of the known methods such as by varying the grid or anode potential of a modulating tube in the amplifier 12. Furthermore, the suppression of the carrier may be obtained by 60 using any one of the known systems such as a balanced modulating circuit well known in the art, the modulation per se forming no part of the present invention. The amplified modulated signals supplied by the tube 16 are impressed 65 through a coupling condenser 18 upon a second

resonant circuit comprised of a capacity 22 and inductances 23, 24 in parallel. Both resonant circuits 19, 20, 21 and 22, 23, 24 are shown to be coupled inductively through the pair of coupling coils 21 and 24 arranged in inductive coupling relation, the former being connected in series with the inductance 20 and the latter in series with the inductance 23. The resonant circuit 22, 23, 24 is coupled to the grid of final amplifying tube 28 by means of condensers 26 and 31 and 10 grid leak 33 in a manner similar to the circuit 19, 20, 21. The output circuits of the tubes 27 and 28 are connected in push-pull by the aid of a transformer having a primary 36 with a center tap connection leading to the positive pole of a 15 common high tension source indicated by the + sign, and a secondary 37 shunted by a tuning condenser 38 and forming the output circuit which may be directly connected to a utilization circuit such as an antenna or the like.

20 In the above equations R_1 represents the ohmic impedances of the circuit 19, 20, 21 and R_2 represents the ohmic impedance of the circuit 22, 23, 24; C_1 corresponds to the capacity 19, and C_2 to the capacity 22; L_1 corresponds to the inductances 25 20, 21 and L_2 to the inductances 23, 24 while M is the inductive coupling coefficient between coils 21 and 24.

Supposing that the circuit 19, 20 and 21 is excited by an electromotive force $A \sin wt$ from the 30 valve 15 and that the circuit 22, 23 and 24 is disconnected from valve 16 and therefore has no potential impressed on it. It will then be found from the above equations that the vectors of the currents in both circuits are in phase quadrature 35 as shown at a and b in Figure 2. Since the circuits 19, 20, 21 and 22, 23, 24 excite the tubes 27 and 28 respectively, the outputs of which are connected in push-pull arrangement, a combined carrier will appear in the common output circuit 37, 40 38 having a phase and amplitude equal to $0A$ as shown in Figure 2, that is, equal to the vector sum of the currents I_1 and I_2 represented by a and b .

If a modulated current in which the carrier has 45 been previously suppressed as represented by $B \sin wt \sin pt$ and obtained in any known manner such as by means of a balanced modulator or the like, is then impressed upon the circuit 22, 23, 24 it is found by analysis from the above Equations I and II that the vectors a and b representing the currents become phase modulated such as 50 illustrated by the diagram of Figure 3. In the latter, the ends of the carrier vectors a and b move along lines d and c in accordance with the 55 variations of the modulating signals. In the output circuits 37 and 38, a pure amplitude modulated current is obtained as illustrated by the vectors $0B$, $0B'$, $0A$. In case of a 100% modulation, the diagram will be as shown in Figure 4. 60 If the constants of the circuits are not exactly equal, that is, if R_1 , R_2 and wM are not alike, then the phase diagram will assume a form as shown in Figure 5 from which it follows that the 65 amplitude modulation in the output current will be proportionate to the original modulating current without any distortion or spurious phase modulation.

The operation and adjustment of the system 70 described is as follows. At first, the modulation in the amplifier 12 is interrupted and both circuits 19, 20, 21 and 22, 23, 24 are exactly tuned to resonance with a very weak coupling between them. After the circuits have been tuned, the coupling is increased until the measuring instru- 75

ments 34 and 35 connected across the condensers 30 and 31, respectively show an equal deflection. After this has been done, both circuits are tuned and the coupling impedance is equal to the ohmic impedances of the circuit provided the latter are designed to have substantially equal values. The vector diagram for this condition is shown in Figure 2. The modulating currents are then impressed through the transformer 13 whereupon the system will operate in the manner described.

From the above it is seen that mutual phase modulation between two or more carrier currents is accomplished in a most simple and efficient manner by means of a phase splitting or twin circuit system of the type described. It will be understood that many variations are possible differing from the details shown for illustration such as the provision of separate driving oscillators for supplying the carrier components in place of a common driver as shown in the drawing.

Referring to Figure 6 there is shown a system for producing a single side band modulated carrier embodying the principle and circuit of the invention. Item 10 is a common driver such as a high frequency oscillator of any known type from which are derived two carrier components which are passed through separate modulating and amplifying channels and impressed upon a common output circuit. The first channel shown comprises a modulator and amplifier 40 having a final stage 46 from which the modulated currents are impressed through a coupling condenser 48 upon one of a pair of phase spreading or twin circuits of the type according to the invention comprising a condenser 50 and an inductance 51 in parallel and a coupling coil 52 in series with the latter. The second channel comprises a modulator and amplifier 41 having a final stage 47 from which the modulated currents are impressed through a coupling condenser 49 upon the other phase spreading or twin circuit comprising a condenser 53 in parallel with an inductance 54 and a coupling coil 55 in series with the latter. The coils 52 and 55 are arranged in inductive relation in a manner similar as shown in the previous figures. Either of the twin circuits 50, 51 and 52 or 53, 54 and 55 may be connected to the input of a common output amplifier 62 by means of a switch 56 through coupling condensers 57 and 58 and a grid leak resistance 59 similar as described in connection with Figure 1. The output circuit of the amplifier 62 includes a tuned transformer 55 having a primary 63 and a secondary 64 shunted by a tuning condenser 65. The output circuit 64, 65 may be connected to a utilization circuit such as an antenna or the like.

The arrangement differs from that shown in Figure 1 by the fact that both carrier components supplied by the driver 10 are modulated by components in phase quadrature of the same modulating signal. Thus, in the example shown, the modulator 41 is connected to a modulating circuit 45 through a low frequency transformer 44 for impressing thereon a modulating component $B \cos pt$. Similarly, the modulator amplifier 40 is connected with a modulating circuit 43 through a transformer 42 for impressing thereon a modulating current $B \sin pt$, that is a current in phase quadrature with the modulating component applied to the modulator 41. Such modulating current components in phase quadrature may be secured in accordance with any one of the well known methods in the art not shown for sake of

simplicity of the description and drawing. Thus, in accordance with one known method, an initial modulating current is employed to modulate an auxiliary carrier frequency wave from which one side band is eliminated such as by means of filters or any other known arrangement. The remaining side band is then combined with a new carrier phase shifted relative to the initial carrier and the resultant current is then demodulated. In this manner, a modulating current is obtained which is 90° phase shifted relative to or in quadrature with the original modulating current. If desired, the carrier may be suppressed by using any one of the known means therefor, such as balanced modulators whereby either the upper or lower side band alone is obtained in the output of the system.

By modulating the separate carrier components in accordance with the quadrature modulating currents as described corresponding carrier potentials are impressed upon the twin or phase spreading circuits 50, 51, 52 and 53, 54, 55. Theoretically, the impressed potentials are represented by the following formulae as indicated in the drawing: $A \sin wt + B \sin wt \sin pt$ impressed upon circuit 50, 51, 52 and $A \sin wt + B \sin wt \cos pt$ impressed upon circuit 53, 54, 55.

By analysis and development of the above Equations I and II, it can be shown that in both circuits 50, 51, 52 and 53, 54, 55 one of the side bands will be suppressed, i. e., if in one of the circuits the upper side band is eliminated the lower side band will disappear in the other circuit and vice versa. In this manner by placing switch 56 in either of the two positions, it is possible to select either the upper or lower modulation side band to be applied to the output circuit 64 and 65. As is understood the above applies to any modulating signal varying in accordance with a complex function which may be resolved into a plurality of sine waves in accordance with well established theory. As is obvious, an arrangement of this type has great advantages in a single side band communication system.

Referring to Figure 7, there is illustrated a phase modulating device or microphone embodying the principle of the invention. A stationary inductance coil 71 is fed from a high frequency source such as an oscillator shown at 72 in series with a tuning condenser 70. A pair of crossed coils 73 and 74 fixed relatively to each other are arranged to rotate about a common axis within the stationary coil 71. The coils 73 and 74 are connected to a diaphragm 75 through a connecting member 76 having one end thereof secured to the common shaft of the coils and having its opposite end supported in a resilient mounting. Thus, the movements of the diaphragm 75 caused by sound variations impinged upon the same are transmitted to the crossed coils 73 and 74 which latter oscillate about their axis in accordance with the variations of the sounds or other modulating variations affecting the diaphragm 75. The coils 73 and 74 are each shunted by a tuning condenser 77 and 78 respectively in series with coupling coils 79 and 80, the latter being arranged in inductive coupling relation to form a pair of phase spreading coupled circuits similar as described hereinabove.

The operation of the system described is as follows. The oscillation of coils 73 and 74 causes currents of different amplitude induced therein from the stationary coil 71 due to varying flux linkage therebetween and the stationary coil 71. 70

Thus, if the constants of the twin circuits are chosen in a manner described hereinabove ($R_1=R_2=wM$) carrier currents of substantially equal amplitude but relative phase shift in accordance with the modulating signal variations are supplied at the output terminals of the twin circuits. As is understood, the coils 73 and 74 may be arranged in fixed position and coil 71 oscillated by the diaphragm 75 to secure the same effect. This function is further illustrated by the diagram in Figure 9 wherein the vectors 0A, 0A' and 0A'' represent the current in one of the twin circuits and the vectors 0B, 0B', 0B'' represent the current in the other twin circuit. The vectors 0A and 0B correspond to the normal condition from which position the vectors move or spread to the left or right in both directions (A', A'' or B', B'' respectively) in accordance with the variations of the modulating magnitude such as the sounds impinged upon the diaphragm 75 in the example illustrated. As is understood the vibratory movement may be imparted to the crossed coils or the stationary coil, respectively by any other suitable drive or pick-up system in place of the diaphragm 25 as illustrated.

Referring to Figure 8, there is shown a complete phase modulating system embodying a modulating device similar to Figure 7. The latter comprises a pair of coaxial movable coils 81 and 82 carried by the diaphragm 75 and both connected in series and fed from the driver 86. Item 85 is a tuning condenser shunted across both coils 81 and 82. The twin or phase spreading circuits are comprised of a pair of fixed inductance coils 83 and 84 shunted by tuning condensers 77 and 78 in series with coupling coils 79 and 80 arranged in inductive relation with each other. The inductance coil of one of the twin circuits 83 is arranged in inductive coupling relation with one of the movable coils 81 operated by the diaphragm 75 and the inductance coil of the other twin circuit 84 is arranged in inductive relation with the other coil 82 operated by the diaphragm. Thus, if sound waves are impinged upon the diaphragm 75, it is seen that the coils 81 and 82 carried by the latter will move in an axial direction in such a manner that one of the coils will approach the associated coil of its twin circuit while the other coil will move away from the coil of its associated twin circuit whereby similarly as in Figure 7 currents having an amplitude differential corresponding to the modulating variations are impressed upon the twin circuits and are transformed into phase modulated currents in the latter in the manner described before. The phase modulated currents are then further amplified preferably by separate amplifiers of which the input stages have been shown at 87 and 88 and may be recombined by means of a push-pull transformer having a primary 89 for utilization in the common output circuit formed by the secondary 90 and tuning condenser 91 in parallel therewith. The use of separate amplifiers for the phase modulated signals prior to their recombination and into amplitude modulated currents has the advantage of greater stability and increased efficiency in the final amplifying stages compared with a common amplifier for the recombined current.

It will be evident from the above that the invention is susceptible of numerous variations and modifications differing from the specific arrangement of parts and methods of operation shown by the above described exemplifications and com-

ing within the broader scope and spirit of the invention as defined in the appended claims. It is intended accordingly that the specification is to be regarded in an illustrative rather than a limited sense.

I claim:

1. In combination, a pair of resonant circuits tuned to substantially the same frequency, a coupling element interconnecting said circuits, the non-reactive impedances of said circuits being substantially equal to one another and to the mutual coupling impedance therebetween, means for impressing potential components of resonant frequency upon said circuits, and further means for varying the amplitude of at least one of the impressed components to effect a corresponding phase shift between the currents developed in said circuits.

2. In a phase modulating system, a source of carrier oscillations, a pair of resonant circuits tuned to the frequency of said oscillations, means for impressing carrier potential components from said source upon said circuits, a coupling element interconnecting said circuits, the non-reactive impedances of said circuits being substantially equal to one another and to the mutual coupling impedance therebetween, and means for varying the amplitude of at least one of the impressed carrier components in accordance with variations of a modulating signal magnitude.

3. In a modulating system, a source of carrier oscillations, a pair of resonant circuits tuned to the frequency of said oscillations, means for impressing carrier potential components from said source upon said circuits, an inductive coupling device interlinking said circuits, the non-reactive impedances of said circuits being substantially equal to one another and to the mutual inductance therebetween, means for varying the amplitude of at least one of the impressed components in accordance with variations of a modulating signal magnitude, and means for combining the currents developed in said circuits.

4. In a modulating system, a source of carrier oscillations, a pair of resonant circuits tuned to the frequency of said oscillations, each of said circuits comprising an inductance and a capacity element in parallel, additional coupling coils in said circuits arranged in inductive coupling relation, means for impressing carrier potential components from said source upon said circuits, the non-reactive impedances of said circuits being substantially equal to one another and to the mutual coupling inductance therebetween, and means for varying the amplitude of at least one of said impressed components in accordance with variations of a modulating signal magnitude.

5. In combination, a source of carrier oscillations, a pair of resonant circuits each tuned to the frequency of said oscillations, means for impressing carrier potential components from said source upon said circuits, a coupling element interconnecting said circuits, the non-reactive impedances of said circuits being substantially equal to one another and to the mutual coupling impedance therebetween, and means for varying the amplitude of at least one of the impressed components to effect a corresponding phase shift between the currents developed in said circuits.

6. In combination, a source of carrier oscillations, a pair of resonant circuits tuned to the frequency of said oscillations, each of said circuits comprising an inductance coil and a condenser in parallel, coupling coils included in said

- resonant circuits and arranged in inductive coupling relation with each other, the non-reactive impedances of said circuits being substantially equal to one another and to the mutual coupling inductance between the circuits, and means for varying the amplitude of at least one of the impressed potentials to effect a corresponding phase shift between the currents developed in said resonant circuits. 5
7. In combination, a source of carrier oscillations, a pair of resonant circuits tuned to the frequency of said oscillations, each of said circuits comprising an inductance coil and a condenser in parallel, said resonant circuits being arranged in mutual coupling relation, the non-reactive impedances of said circuits being substantially equal to one another and to the mutual coupling impedance between the circuits, means for varying at least one of the impressed potentials in accordance with variations of a modulating signal magnitude to cause corresponding phase modulated currents in said circuits, and a push-pull amplifier having its input controlled by both said resonant circuits to secure a resultant amplitude modulated current in the output thereof. 10
8. In combination, a pair of resonant circuits tuned to substantially the same carrier frequency, means for impressing carrier frequency potential components upon said circuits, a coupling element interconnecting said circuits, the non-reactive impedances of said circuits being substantially equal to one another and to the mutual coupling impedance between the circuits, means for modulating the relative amplitude of the potentials impressed upon said circuits in accordance with a modulating signal by currents substantially equal to but in phase quadrature with each other, and means for utilizing the current developed in either of said resonant circuits. 15
9. A phase modulator comprising a pair of inductance coils arranged in fixed relation to each other, a tuning condenser connected across each of said coils to form a pair of resonant circuits tuned to substantially the same frequency, said resonant circuits being arranged in mutual coupling relation, the non-reactive impedances of said resonant circuits being substantially equal to one another and to the coupling impedance between the circuits, means for impressing upon said circuits carrier potentials of resonant frequency having a predetermined amplitude relation to produce currents in said circuits having a time phase relation substantially in accordance with said amplitude relation. 20
10. A modulator comprising a pair of inductance coils, tuning condensers connected across said coils to form a pair of resonant circuits tuned to a predetermined carrier frequency, said circuits being inductively coupled, the non-reactive impedances of said circuits being substantially equal to one another and to the mutual inductive impedance therebetween, means for impressing carrier potentials of predetermined amplitude relation upon said circuits to produce currents therein of substantially equal amplitude but having a time phase relation equal to said amplitude relation, and means for combining said currents to produce a resultant amplitude modulated current. 25
11. A phase modulator comprising a pair of inductance coils, tuning condensers connected across said coils to form a pair of resonant circuits tuned to a predetermined carrier frequency, said circuits being inductively coupled with each other, the non-reactive impedances of said circuits being substantially equal to one another and to the mutual inductive impedance therebetween, means for impressing carrier potentials of predetermined amplitude relation upon said circuits to produce currents therein of substantially equal amplitude but having a time phase relation equal to said amplitude relation, and means for combining said currents to produce a resultant amplitude modulated current. 30
12. In combination, a pair of resonant circuits tuned to substantially the same frequency, means for impressing potentials of resonant frequency upon said circuits, reactive coupling means arranged to effect a mutual interchange of resonant energy between said circuits, said coupling means being adapted to produce a predetermined normal phase relation between the currents in said circuits when the potentials impressed thereon are of predetermined relative magnitude, further means for varying the relative magnitude of the potentials impressed upon said circuits, and a utilization circuit connected to at least one of said resonant circuits. 35
13. In combination, a pair of resonant circuits tuned to substantially the same frequency, means for impressing potentials of resonant frequency upon said circuits, reactive coupling means arranged to effect a mutual interchange of resonant energy between said circuits, said coupling means being adapted to produce a predetermined normal phase relation between currents in said circuits developed by the impressed potentials of predetermined relative magnitude, means for varying the relative magnitude of said potentials, thereby to correspondingly vary the relative phase of said currents in respect to their normal phase relation, a utilization circuit connected to at least one of said resonant circuits, and means for preventing reaction from said utilization circuit upon said coupling means. 40
14. In combination, a pair of resonant circuits, each comprising inductance means shunted by a condenser and tuned to substantially the same frequency, means for impressing potentials of resonant frequency upon said circuits, portions of said inductance means being in inductive coupling relation to effect a mutual interchange of resonant energy between said circuits, the effective coupling between said circuits being adapted to produce a predetermined normal relation between the currents in said circuits developed by impressed potentials of predetermined relative magnitude, means for varying the relative magnitude of the impressed potentials to correspondingly vary the relative phase of said currents in respect to their normal phase relation, and a utilization circuit connected to at least one of said resonant circuits. 45
15. In combination, a pair of resonant circuits comprising substantially equal inductance means shunted by equal condensers, means for normally impressing a potential of resonant frequency upon at least one of said circuits, portions of the inductance means of said circuits being in coupling relation to effect a mutual interchange of resonant energy between said circuits, the effective mutual coupling being adapted to produce a predetermined normal phase relation of the currents developed in said circuits by the impressed potentials of predetermined relative magnitude, and further means for impressing additional potentials upon at least one of said circuits to correspondingly vary the relative 50
- 70
- 75

- phase of said currents in respect to their respective phase, and a utilization circuit connected to at least one of said resonant circuits.
16. In a phase modulation system, a source of carrier oscillations, means for producing a modulated carrier-suppressed component from said oscillations, a pair of resonant circuits tuned to the carrier frequency, coupling means between said circuits to effect a mutual interchange of resonant energy therebetween, said coupling means being adapted to effect a predetermined normal phase relation between the currents in said circuits developed by impressed potentials of predetermined relative magnitudes, means for impressing an unmodulated component of said carrier oscillation upon one of said circuits, and further means for impressing said modulated carrier-suppressed component upon said other resonant circuit.
17. In a phase modulation system, a source of carrier oscillations, a pair of resonant circuits tuned to the carrier frequency, reactive coupling means interconnecting said resonant circuits to effect a mutual interchange of resonant energy therebetween, means for deriving a carrier potential from said source and for impressing the same upon one of said circuits, means for independently deriving a further carrier potential from said source, means for amplitude modulating said latter carrier potential in accordance with variations of a signal magnitude, and further means for impressing the modulated component of said latter carrier potential upon said other resonant circuit, an output circuit differentially coupled to both said resonant circuits, and means to prevent reaction from said output circuit upon said coupling means.
18. A phase modulator comprising a pair of resonant circuits, each comprising an inductance coil, said inductance coils arranged in fixed relation relative to each other, a third inductance coil arranged in inductive coupling relation to both said first inductance coils, reactive coupling means interconnecting said resonant circuits to effect a mutual interchange of resonant energy therebetween, said coupling means being adapted to produce a predetermined normal phase relation between the currents in said resonant circuit caused by impressed potentials of predetermined relative magnitude, means for impressing a resonant carrier potential upon said third inductance coil, a mechanical translating device, and means for translating the movements of said device into relative movements between said pair of fixed inductance coils and said third inductance coil.
19. In combination, a source of high frequency energy, a pair of mutually fixed coils movably arranged in a high frequency field provided by said source, condensers connected to said coils to form resonant circuits tuned to the frequency of said source, reactive coupling means between said circuit adapted to effect a mutual interchange of resonant energy therebetween to produce a normal phase shift be-

tween the currents in said circuits at a predetermined position of said coils in said high frequency field, actuating means for displacing said coils relative to said predetermined position, an amplifier connected to at least one of said resonant circuits, and a utilization connected to the output of said amplifier.

20. In a combination, a source of high frequency energy, a pair of mutually perpendicular coils arranged rotatably about a common axis in a high frequency field provided by said source, condensers connected to said coils to form resonant circuits tuned to the frequency of said source, reactive coupling means between said circuits adapted to effect a mutual interchange of resonant energy therebetween to produce a normal predetermined phase shift between the currents in said resonant circuits at a predetermined position of said coils in said high frequency field, actuating means for oscillating said coils in accordance with a varying magnitude to be translated, an amplifier connected to at least one of said resonant circuits, and a utilization circuit connected to the output of said amplifier.

21. In combination, a source of high frequency energy, a pair of induction coils fixed relative to each other and arranged to be movable in unison in a high frequency field provided by said source, condensers connected to said coils to form resonant circuits tuned to the frequency of said source, reactive coupling means between said resonant circuits adapted to effect a normal predetermined phase shift between the currents in said circuits at a predetermined position of said coils in said high frequency field, means for actuating said coils to differentially vary the magnetic flux therethrough by said high frequency field to cause corresponding phase modulation of the currents in said resonant circuits, amplifiers connected to said resonant circuits, and a common utilization circuit fed by the output of both said amplifiers to produce amplitude modulated energy therein.

22. In combination a source of high frequency energy, a pair of crossed induction coils rotatably arranged about a common axis in a high frequency field provided by said source, condensers connected to said coils to form resonant circuits tuned to the frequency of said source, inductive coupling means between said circuits adapted to effect a normal predetermined phase shift between the currents in said resonant circuits at a predetermined position of said coils in said high frequency field, means for oscillating said coils to vary the magnetic flux therethrough provided by said high frequency field to cause corresponding differential phase modulation of the currents in said resonant circuits, amplifiers connected to said resonant circuits, and a common utilization circuit fed by the outputs of both of said amplifiers to produce amplitude modulated energy therein.
